United States Patent Office

Des. 208,902
Patented Oct. 17, 1967

208,902

SLIPPER

Basil D. Huff, Wilkes-Barre, Pa. (½ Charles Sonnereich, 1501 Broadway, New York, N.Y. 10036)

Filed Dec. 6, 1966, Ser. No. 4,942

Term of patent 7 years

(Cl. D2—293)

FIG. 1

FIG. 2

FIG. 3

FIG. 4

FIG. 1 is a side perspective view of a slipper showing my new design.

FIG. 2 is the opposite side of that shown in FIG. 1.

FIG. 3 is a bottom plan view.

FIG. 4 is a plan view of the slipper in open flat position.

I claim:

The ornamental design for a slipper, substantially as shown.
